UNITED STATES PATENT OFFICE.

RICHARD C. NEPTUNE, OF ST. LOUIS, MISSOURI.

ROOFING.

Application filed April 10, 1922. Serial No. 551,016.

To all whom it may concern:

Be it known that I, RICHARD C. NEPTUNE, a citizen of the United States, and a resident of the city of St. Louis and State of 5 Missouri, have invented a certain new and useful Improvement in Roofings, of which the following is a specification.

My invention relates to roofing of the kind commonly referred to as prepared roofing. 10 Such roofing is extensively marketed in rolls of long strips and has an ornamental design printed thereon. Heretofore it has been customary to discontinue the printed pattern short of the "upper" margin of the 15 sheet, that is, to leave the "upper" margin blank or unprinted, usually for a width of about two inches. On account of this marginal portion being left blank, it is necessary in practice, that the blank margin be 20 covered by the margin of a superposed sheet in order for the patterns thereof to match; and when such roofing is to be used on a hip roof, it is necessary to cut the strips into trapezoidal sections whose long edges shall 25 all come from the same edge of the strip; that is, although one parallel side of each section is considerably shorter than the other side of the same section, the strip from which they are cut must be as long as the 30 total of the long sides of the several sections. According to present practice, the matching of roofing thus entails a very large waste of material, the amount of waste being proportionate to the difference 35 in length between the two parallel sides of the section.

The principal object of the present invention is to save the material now wasted by reason of the inability of the figured roofing 40 to match, in reversed position.

The invention consists principally in a figured roofing of which sections cut therefrom will match equally well in normal or reversed position; it also consists in a figured roofing, wherein the imprint extends to both margins of the strip and wherein the figures are complete throughout the body of the roofing and fractional along the side margins for width suitable for a lap joint, the design being identical along its opposite 45 side margins but disposed in opposite directions.

In the accompanying drawing wherein like reference characters refer to like parts 50 wherever they occur,

Fig. 1 is a view of a strip of roofing con-

forming to my invention, the dotted lines therein marking off trapezoidal sections such as is needed for use on a hip roof; and

Fig. 2 is a view showing the manner of 60 assembling the trapezoidal sections, the dotted lines indicating the outline of the under or overlapped section.

The longitudinal shade lines along one border X of the strip and the transverse 65 shade lines along the other border Y, appearing in the accompanying drawing, are not part of the imprint and do not appear on the roofing, but are used in the drawing as a means of marking off the side marginal 70 portions from the body portion of the strip and maintaining the identity of such margins in the drawing even when their positions are reversed.

My roofing comprises a strip A of roofing 75 of any of the kinds variously known as prepared roofing, strip roofing or roll roofing. One face of this roofing is "figured", that is, has imprinted thereon repetitions of any suitable unit or pattern. Preferably the 80 pattern (or patterns) is repeated in one or more rows extending longitudinally of the strip; and the individual pattern or unit 10 is symmetrical. The imprint or figuring reaches from one side edge of the strip to 85 the opposite side edge. The marginal portion X along one side edge for a width suitable for a lap seam, say about two inches, bears the same imprint as the marginal portion Y of the same width along the 90 opposite edge; but the arrangement along one edge is the reverse of that along the other edge, that is, comparing the lower margin X of the strip and the lower margin Y of the strip, the parts of the individual 95 pattern that are uppermost in the lower margin are lowermost in the upper margin, and the parts that are at the right in the lower margin are at the left in the upper margin. In consequence of this arrangement, 100 when the sheet is turned end for end, it presents the same appearance as in its first position.

In consequence of the two marginal portions of the strip bearing the same imprint 105 in reverse, sections, such as A¹, A², A³ from the same strip may be matched with either margin over-lapping, as due allowance having been made in the imprinting for the lap, the sections will match equally well whether 110 laid in their initial relative positions or with one section reversed end for end rela-

tive to the section to be matched. For the purpose of description, the strip may be considered as made up of side marginal portions X Y intended for the lap, which 5 extend inwardly from the respective side edges, to the nearest points of the complete figures or units of pattern, and a body portion extending from one such side marginal portion to the other. In such case, the complete 10 figures or units of design are located in the body portion of the strip, and only fractional parts of such figures or units are located in the marginal portions. When the figures are disposed corner to corner in longitudinal rows, as shown in the drawing, the fractional figures comprise small fractions 15 11 in the marginal or lap portions alternating with large fractions 12 that are the geometrical complement of such small fractions 20 and that comprise a half unit 13 in the body of the strip and a smaller part 14 in the marginal portion intended for the lap.

In consequence of the capacity for matching when reversed end for end, it is possible 25 to cut the strip into sections with oblique ends needed for fitting hip roofs without wasting any of the material on this account. In other words, the invention enables the roofer to save the material heretofore wasted in cutting trapezoidal sections.

Thus, as illustrated in the accompanying drawing, the trapezoidal sections A^1 , A^2 and A^3 may be cut from the strip A of roofing for use on a hip roof. As illustrated, section 35 A^2 is reversed end for end and used below section A^1 , the margin Y of section A^2 underlapping the margin Y of section A^1 . In such cases, the oblique end section A^3 of the strip may be joined by proper seam to another section of sufficient length to piece out the run.

While I have shown one particular design, I do not wish to be restricted thereto, as the invention does not depend upon any 45 particular design but upon the capability of the figured strip being cut into sections that will match along both sides and this capacity depends on the two marginal portions of the sheets bearing the same imprint in reverse.

50 What I claim is:

1. Strip roofing having its entire width from side edge to side edge imprinted with repetitions of a reversible unit of design, the distances between the respective side edges 55 of the strip and the nearest points of the

complete units being equal and of a width to provide a standard lap joint, such marginal portion along one edge being the same as to imprint as the corresponding portion along the opposite edge when placed in the same 60 position, whereby sections of said roofing will match when lapped in either normal position or when one is reversed end for end.

2. Strip roofing having a selected pattern 65 imprinted thereon in longitudinal rows wherein the figure is complete throughout the body portion of the roofing and fractional along the side margins thereof, the distance from the respective side edges of 70 the sheet to the nearest complete figures being of a width to provide a standard lap joint and being the same as to imprint when placed in the same position, whereby sections of said roofing will match when such 75 marginal portions are lapped in either normal position or when one is reversed end for end.

3. Figured strip roofing imprinted from side edge to side edge with repetitions of 80 a selected symmetrical figure or figures plus fractions thereof along the respective sides, one series of such fractions being relatively small and extending inwardly from each side edge for a width to provide a standard 85 lap joint, and the other fractions being the geometrical complement of the small fractions and alternating therewith, the marginal portion along one side edge of the strip having the same imprint as the marginal portion along the opposite edge but in symmetrically reverse position. 90

4. Figured strip roofing imprinted from side edge to side edge with repetitions of a reversible unit or units of design and fractions thereof, said roofing comprising a body portion wherein the design appears in complete units and halves thereof, and side marginal portions being of a width to provide a standard lap joint whereon there are only 100 relatively small fractional parts of the unit of design, the marginal portion along one side edge of the strip having the same imprint as the marginal portion along the opposite edge but in symmetrically reverse 105 position.

Signed at Indianapolis, Indiana, this 6th day of April, 1922.

RICHARD C. NEPTUNE.

Certificate of Correction.

It is hereby certified that in Letters Patent No. 1,444,550, granted February 6, 1923, upon the application of Richard C. Neptune, of St. Louis, Missouri, for an improvement in "Roofings," an error appears in the printed specification requiring correction as follows: Page 1, line 93, for the word "lower" read *upper*; and that the said Letters Patent should be read with this correction therein that the same may conform to the record of the case in the Patent Office.

Signed and sealed this 20th day of March, A. D., 1923.

[SEAL.]

KARL FENNING,
Acting Commissioner of Patents.
